(21) Appl. No.: **29/355,268**

(57) **CLAIM**

(22) Filed: **Feb. 4, 2010**

The ornamental design for a tread portion of an automobile tire, as shown and described.

(51) **LOC (9) Cl.** 12-16

DESCRIPTION

(52) **U.S. Cl.** **D12/583**

FIG. 1 is a front view of a tread portion of an automobile tire; FIG. 2 is a perspective view thereof; FIG. 3 is a left side view thereof; and, FIG. 4 is a fragmentary enlarged view showing the details of the tread portion thereof.

(58) **Field of Classification Search** D12/582-585,

The broken lines defining the sidewall and inner bead of the tire depict environmental subject matter that forms no part of the claimed design.

D12/571, 579; 152/209.1, 209.12, 209.18,
